SWITCH & SIGNAL COMPANY, OF SWISSVALE, PENNSYLVANIA, A CORPORATION
OF PENNSYLVANIA.

SLOW-ACTING DEVICE.

1,310,500.

Specification of Letters Patent. Patented July 22, 1919.

Application filed May 14, 1918. Serial No. 234,565.

To all whom it may concern:

Be it known that I, WALTER P. NEUBERT, a citizen of the United States, residing at Pittsburgh, in the county of Allegheny and 5 State of Pennsylvania, have invented certain new and useful Improvements in Slow-Acting Devices, of which the following is a specification.

My invention relates to slow-acting devices, and particularly to devices of this 10 character which depend for their action on the flow of a fluid through a restricted orifice. Devices embodying my invention are well adapted for use in connection with apparatus for the control of railway switches 15 and signals, although they are not limited to this particular field.

I will describe one form of slow-acting device embodying my invention and will 20 then point out the novel features thereof in claims.

In the accompanying drawings, Figure 1 is a view showing in vertical section one 25 form of device embodying my invention. Fig. 2 is a view, partly in elevation and partly sectioned, taken at right angles to Fig. 1 and showing the upper portion of the device shown in Fig. 1.

Similar reference characters refer to similar 30 parts in each of the several views.

Referring first to Fig. 1, the device in the form here shown comprises a hollow cylindrical member 1, the lower inner rim of which is threaded to receive a cap 2. The 35 inside of the rim at the bottom of cap 2 is likewise threaded to receive a second cap 3. Passing through the cap 2 at one side thereof is an opening 2^a. The cylindrical member 1, the opening 2^a in cap 2, and the 40 cap 3, constitute an outer fluid container which I will designate collectively by the reference character O. Located inside of this container is a cylindrical member 4 mounted in cap 2 and comprising, with this 45 cap, a second or inner fluid container designated collectively as I. The upper end of member 4 is located below the top of the outer container O, and this member 4 is not provided with a cap at its upper end. Hence 50 it follows that the two fluid containers communicate with each other at the top, the opening between the two being of considerable area. Another opening is provided between these two containers, in the form of

a hole 2^b extending through the cap 2 at 55 the bottom of the inner container. The effective area of this opening may be varied by means which I will describe hereinafter.

Located within the inner container I is a hollow cylindrical plunger 5 to which is attached a rod 6 extending upwardly and co-acting with any suitable apparatus such as that which will be described hereinafter. The plunger is of such size as to be movable within the container I with a small 60 amount of clearance. The inner and outer containers are filled, to about the level indicated, with a fluid 7 having sufficient specific gravity to float the plunger 5; this fluid is preferably mercury.

It will now be apparent that when the plunger 5 is forced downwardly from the position in which it is shown, some of the fluid in the inner container, that is, some of the fluid between the plunger 5 and the 70 member 4, will be driven upwardly and will spill over into the outer container O. The downward movement of the plunger is not retarded to an appreciable amount because of the large opening between the two containers at the top of the member 4. When the pressure on the plunger is removed, the fluid which was transferred from the inner to the outer container returns through the opening 2^b, and in so doing it raises the 75 plunger to its initial position, that is, to the position in which it is shown in the drawing. This return or upward movement is comparatively slow, however, because of the 80 comparatively small area of the opening 2^b, and of course the time required for the complete return movement of the plunger to be accomplished will vary with variations in the area of this opening.

The effective area of opening 2^b is controlled by a conical valve 8 which may be moved into and out of the opening, so that the effective area is comparatively large when the valve is all the way out, and comparatively small or zero when the valve is 85 in as far as it will go. This valve is attached to a flexible diaphragm 9 which is supported between the two caps 2 and 3, and owing to its location it constitutes the lower 90 wall of the outer fluid container O. This 100 diaphragm is, consequently, subject to the pressure of the mercury in the outer container, and by virtue of this pressure it is 105

constantly biased to such position that the valve 8 is entirely out of opening 2^b, that is, to such position that the effective area of the opening is maximum. To raise the diaphragm, and consequently the valve 8, I provide a screw 10 which passes through a threaded hole in the cap 3 and which abuts against the end of a screw 11 carried by the diaphragm. It will be clear that by turning the screw 10 in one direction or the other, the diaphragm 9 may be raised against the action of the fluid pressure or may be allowed to fall due to the action of the fluid pressure, and so the effective area of the opening 2^b may be varied by infinitely small increments between the two extreme values.

One important feature of my present invention, then, is the provision of means for adjusting the effective area of the opening 2^b from the outside of the outer fluid container, so that this adjustment can be made without removing any part of the device. Another important feature is the provision of means for varying the effective area of this opening by infinitely small increments.

In a slow-acting device of this character it is of course desirable that the force tending to lift the plunger 5 be as great as practicable, and that this force be substantially as great when the plunger is near the upper end of its stroke as when it is at the lower end. To accomplish this result, the level of the fluid must be kept high, so as to provide as great a "head" as possible. In order to do this with the minimum amount of fluid, I construct the device in such manner that the horizontal area of the space between the plunger and the inner container is as small as practicable, and that likewise the horizontal area of the space between the inner and outer containers is as small as practicable except near the level of the fluid where the outer container is widened out as shown to provide an overflow chamber. This overflow chamber is of such size that the level of the fluid therein is substantially the same when the plunger is at the top of its stroke as when the plunger is at the bottom of its stroke, hence the "head" of the fluid is substantially the same for all positions of the plunger and is comparatively great for a comparatively small quantity of fluid.

The upper end of the plunger 5 is preferably provided with an umbrella-shaped top 5^a to deflect the fluid on the down stroke of the plunger. This prevents the fluid from passing up between the rod 6 and the housing around this rod, and squeezing out at the top of the device.

The plunger 5 may be actuated by any suitable means, and may in turn be employed to control any suitable means. As here shown, the upper end of the rod 6 co-acts with a segment 12 which is attached to

a shaft 13 of an interlocking machine such as is commonly employed for the control of railway switches and signals. Attached to the rod 6 is a yoke 14 which straddles the segment 12 as shown in Fig. 1. When the shaft 13 and segment 12 are in their middle position as shown in Fig. 2, the plunger 5 is at the top of its stroke. If now the shaft and segment are turned in clockwise direction as viewed in Fig. 2, the lug 12^a on segment 12 will depress the plunger 5; the segment may then be returned toward its middle position but will be stopped by the engagement of the shoulder 12^b and the upper arm of yoke 14. The segment is locked in this mid-stroke position for the period of time required for the plunger to rise to its upper position, whereupon the segment is released and may then be returned to its middle position.

Although I have herein shown and described only one form of slow-acting device embodying my invention, it is understood that various changes and modifications may be made therein within the scope of the appended claims without departing from the spirit and scope of my invention.

Having thus described my invention, what I claim is:

1. A slow-acting device comprising outer and inner fluid containers, a plunger within the inner container, fluid in said containers of sufficient specific gravity to float said plunger, said containers communicating with each other above the highest level of the fluid in the outer container, an opening through the inner container below the lowest level of the fluid in the outer container, a valve coöperating with said opening to vary the effective area thereof, and means extending through the outer container for moving said valve.

2. A slow-acting device comprising outer and inner fluid containers, a plunger within the inner container, fluid in said containers of sufficient specific gravity to float said plunger, said containers communicating with each other above the highest level of the fluid in the outer container, an opening through the inner container below the lowest level of the fluid in the outer container, a valve coöperating with said opening to vary the effective area thereof, and means for moving said valve from outside of said outer container.

3. A slow-acting device comprising outer and inner fluid containers, a plunger within the inner container, fluid in said containers of sufficient specific gravity to float said plunger, said containers communicating with each other above the highest level of the fluid in the outer container, an opening through the inner container below the lowest level of the fluid in the outer container, and means located partly within said outer con-

tainer and extending to the outside thereof for varying the effective area of said opening.

4. A slow-acting device comprising outer and inner fluid containers, a plunger within the inner container, fluid in said containers of sufficient specific gravity to float said plunger, said containers communicating with each other above the highest level of the fluid in the outer container, an opening through the inner container below the lowest level of the fluid in the outer container, a flexible diaphragm in said outer container subject to the pressure of said fluid on one side but not on the other, a valve carried by said diaphragm and coöperating with said opening to vary the effective area of the latter, and means extending through said outer container for moving said diaphragm in opposition to the pressure of said fluid thereon.
5. A slow-acting device comprising outer and inner fluid containers, a plunger within the inner container, fluid in said containers of sufficient specific gravity to float said plunger, said containers communicating with each other above the highest level of the fluid in the outer container, an opening through the inner container below the lowest level of the fluid in the outer container, a flexible diaphragm in said outer container subject to the pressure of said fluid on one side but not on the other, a valve carried by said diaphragm and coöperating with said opening to vary the effective area of the latter, and a screw passing through a threaded

hole in said outer container to move said diaphragm.

6. A slow-acting device comprising inner and outer fluid containers, a plunger within the inner container, fluid in said containers of sufficient specific gravity to float said plunger, said containers communicating with each other by two openings located respectively above and below the level of the fluid in the outer container, the horizontal area of the space between the plunger and the inner container being comparatively small, and the horizontal area of the space between the two containers being comparatively small throughout the greater part of the vertical height of the fluid in the outer container but comparatively large near the level of the fluid in the outer container.

7. A slow-acting device comprising inner and outer fluid containers, a plunger within the inner container, fluid in said containers of sufficient specific gravity to float said plunger, said containers communicating with each other by two openings located respectively above and below the level of the fluid in the outer container, said plunger being provided with a shield to deflect fluid which is forced upwardly when the plunger is forced downwardly.

In testimony whereof I affix my signature in presence of two witnesses.

WALTER P. NEUBERT.
